LABELING MACHINE

Carl Holm, Worcester, Mass., assignor to Economic Machinery Company, Worcester, Mass., a corporation of Massachusetts

Application June 5, 1946, Serial No. 674,469

37 Claims. (Cl. 216—55)

1

This invention pertains to the art of label pasting and affixing, and relates more particularly to a novel label-applying machine of the kind wherein labels, arranged in a magazine, are removed one by one by an adhesively coated picker. The machine herein described by way of example, as illustrative of the novel principles involved, is of the semi-automatic type, but it may be understood that in its broader aspects at least, the invention is applicable to machines of the full automatic type.

The coating of labels with adhesive and the proper application of the coated label to the article is an operation which is attended with many practical difficulties, and in the effort to avoid these difficulties designers of such machines have heretofore commonly resorted to multiplication of parts, complexity of operation, and in many instances to structures of large overall dimensions, so that such machines are expensive, require highly skilled attendants and service, and occupy more space than is sometimes available.

Customarily a picker of the adhesive type consists of two or more label-engaging parts which are spaced or at least separable to permit a transfer element or presser to enter between them in applying the label to the article designed to receive it. Such a divided picker, with its associated transfer or presser element, can not be depended upon to deliver the label accurately to the article to be labeled; it is not capable of handling very small labels; and it tends to accumulate gum to an extent such that it must be cleaned at frequent intervals to prevent the gum from dripping. While pneumatic pickers for removing the labels from the magazine, are effective, such pickers are more complicated than those of the adhesive type, and necessitate the application of gum directly to the label while the latter is adherent to the picker, requiring the employment of gum-applying means of elaborate type.

In accordance with the present invention, most of the difficulties attendant upon the use of previous types of picker are avoided; accuracy of label positioning is assured; labels of all sizes may be handled with substantially equal facility and speed; the gum is applied uniformly and without waste to the surface of the label; and the mechanism employed is of simple character. In the attainment of these advantages an adhesive type picker is employed which is of unitary character (that is to say, it is not divided to permit the passage of a transfer element between its several parts) and which is of substantially the same shape and external dimensions as the label

2

to be applied; the label is transferred from the picker to a transfer device, applier or carrier which carries the label to and deposits it upon the article to be labeled, and during the transfer from the picker to the applier or carrier, the picker is so moved relatively to the label as to cause the picker to slide while in contact with the adhesive coating on the label so as to spread the coating uniformly over the label.

10 Principal objects of the present invention are to provide a machine of the class described (and having the novel characteristics just above pointed out) which is simple in construction and in operation, compact in design, occupies a minimum amount of space and has relatively few parts; which may be manufactured at relatively low cost as compared with most prior machines of this type; which is substantial and durable; and which does not require highly skilled attendants or service. A further object is to provide simple means to insure the uniform spreading of the adhesive over the surface of the label without danger of waste of adhesive, or the smearing of adjacent parts. A further object is to provide 15 means operative to prevent removal of labels from the magazine in the event that there is no article in position to receive a label or until, in starting the machine, the picker has been adequately supplied with adhesive. Other and further objects and advantages of the invention will be pointed out in the following more detailed description and by reference to the accompanying drawings wherein

Fig. 1 is a fragmentary elevation, partly in 20 vertical section, and with parts omitted and broken away, the machine being viewed from its right-hand side, and showing the parts in the relative positions which they occupy while the label is being pressed onto the article being 25 labeled;

Fig. 2 is a side elevation, to larger scale, illustrating a preferred form of picker;

Fig. 3 is a fragmentary side elevation, partly in vertical section and omitting many parts, and 30 showing the machine at that instant in its operation when the label is first applied to the article and before the label has been pressed into place;

Fig. 4 is a fragmentary front elevation of the machine, partly in vertical section and with 35 many of the parts omitted or broken away;

Fig. 5 is a side elevation of the cam which actuates the transfer device or applier;

Fig. 6 is a side elevation of the cam which actuates the device for holding the transfer device or applier firmly in position during the

transfer of the label from the picker to the applicer;

Fig. 7 is a side elevation of the cam which moves the picker up and down;

Fig. 8 is a side elevation of the cam which moves the picker from front to rear;

Fig. 9 is a side elevation of the cam which actuates the presser pad for firmly pressing the label against the article; and

Fig. 10 is a diagrammatic composite view showing the relative positions of the several cams when mounted upon the drive shaft, the latter being shown in section.

Referring to the drawings, the base of the machine is indicated at 1, this base constituting a support for a drive motor, a drive clutch control pedal, and such other customary elements as may be desirable, but which are not herein illustrated, since they may be of conventional type and form no essential part of the present invention.

The frame of the machine rests upon and is rigidly secured to the base 1. As here illustrated by way of example, but without limitation as to exact details, the frame comprises spaced parallel uprights 2 and 3, conveniently castings, flanged for strength, and provided with integral bosses or pads where necessary to form bearings or supports for shafts or other parts. These uprights 2 and 3 are bolted at their lower ends to the base 1 and are connected at their upper ends by the transfer top rail 4 which is also a casting as herein illustrated.

An upstanding bracket 5 is fixed at its lower end to the front of the base 1 and is provided at its upper end with a finished vertical face 6 (Fig. 1) against which the vertically adjustable stem 7 of an article-supporting cradle 8 is clamped by means of a bolt or bolts 9.

A horizontal, transverse drive shaft 10 is supported to turn in bearings in the uprights 2 and 3. A gear 11, near the right-hand end of the shaft 10, is mounted to turn freely on the shaft, and is constantly turned while the machine is in operation by the motor mounted on the base 1. Preferably a train of gears transmits motion from the motor to the gear 11, although any suitable transmission means may be employed for driving the gear 11 from the motor. Since this transmission forms no essential part of the invention, this train of driving gears is not shown. The gear 11 may be clutched to the shaft 10, so as to drive the latter, by means of a clutch 12 of conventional type, actuated by the foot pedal above referred to and not herein shown.

Crank 13 (Fig. 4) fixed to the left-hand end of the shaft 10, actuates the piston rod 14 of a vacuum pump 15 mounted on the outside of the upright 2. Actuating cams for the various operative elements of the machine are fixed to the shaft 10 between the uprights 2 and 3 and will be more fully described hereinafter.

Parallel rigid guide rods 16 and 17 (Figs. 1 and 4), which slope downwardly and forwardly, are supported at their opposite ends in brackets carried by the frame. A magazine carriage 18 (Fig. 1) is mounted to slide on these rods. The frame 19 of a label magazine M is mounted on this carriage. The magazine may be of any appropriate construction, for example, such as is common in the labeling art and designed to hold a stack of labels L (Fig. 1) so that the endmost forward label is disposed in a substantially vertical plane and exposed for removal by the picker.

In its forward position the magazine is so

located that the picker, in its normal travel, will contact and remove the exposed end label from the magazine. However, there are times, for example, when first starting the machine or when no article is in position to receive a label, when the removal of labels from the magazine should be prevented. To this end, the magazine is movable rearwardly out of its normal position so that the picker can not contact the exposed endmost label. For positioning the magazine a link 20 (Fig. 1) is pivotally secured at its forward end to the magazine carriage 18 and at its rear end to the normally horizontal arm 21 of a bell crank lever fulcrummed on a shaft 22, said lever having a downwardly and forwardly directed arm 23 to which is pivotally connected the lower rear end of a link 24. The upper end of this link 24 is pivoted at 25 to one arm 26 of a bell crank lever fulcrummed on a shaft 27, and having a long forwardly directed arm 28 provided at its front end with a handle 29. By swinging the arm 28 upwardly the link 20 is moved rearwardly, thus moving the magazine far enough to the rear to prevent the picker from engaging the endmost label in the magazine.

The picker is a plate of substantially the same shape and dimensions as the label to be applied. It is of unitary construction, that is to say, it is not divided into spaced or separable parts. It is designed to be registered with the endmost label in the magazine and to cover the entire surface of the label. While the picker plate may, if desired, consist of several parts properly assembled and rigidly united, it is preferably a single piece of material, for example, a single casting. As illustrated in Fig. 2, this picker plate has a single, uninterrupted, flat gum-receiving face 32 of substantially the same size and shape as the label. However, in accordance with a modification illustrated in Fig. 2a, the adhesive-receiving face of the plate 30 may be divided by a series of parallel channels 31 so as to provide a corresponding series of narrow, parallel adhesive-receiving faces 32a. However, these faces 32a are fixed relatively to each other, and the body portion of the plate is uninterrupted between its lateral edges.

The plate 30 has a boss 33 at its forward side which is removably attachable to a horizontal arm 34 (Fig. 4) extending laterally from the picker carriage 35. It is to be understood that this picker plate 30 is interchangeable with generally similar plates of appropriate size and shape for use with any selected label. The carriage is mounted to slide up and down upon a vertically elongate swinging guide 36. This guide is a flat bar whose upper end is fixed to a swivel member 37 mounted to rock on a stub shaft 38 fixed to the upright 2. The lower end of this flat guide bar 36 is pivotally attached to the forward end of a link 39 (Figs. 3 and 4) whose rear end portion is arranged to slide in a guide boss 40 on the forward end of a yoke 41, pivotally connected at its rear end, at 42, to the upper end of a lever 43. The lower end of the lever 43 is fulcrummed on a pin 44 (Fig. 3) carried by the frame. A cam follower roll 45, mounted on the lever 43 intermediate its ends, engages a cam groove 46 (Fig. 8) in a cam disk 47 fixed to the main shaft 10. The rear end of the link 39 has a fixed head or collar 48, and a coiled spring 49 is interposed between this collar and the boss 40, the spring providing a yielding connection between the yoke and link.

The picker carriage 35 is disposed at the rear side of the flat guide rod 36 so as to slide up and

down in contact with said rear surface, but is provided with anti-friction rolls 50 (Fig. 3) which engage the front surface of the guide rod 36 and which keep the carriage operatively associated with the rod.

A link 51 is pivotally secured at its upper end to the picker carriage 35 and at its lower end to the forward end of a lever 52. This lever 52 (Fig. 3) is fulcrumed at its rear end upon a pin 53 carried by the frame and has a cam follower roll 54 intermediate its ends which is received in a cam groove 55 (Fig. 7) in a cam disk 56, fixed to the drive shaft 10. Rotation of the cam disk 56 thus moves the picker carriage up and down along the guide rod 36, while rotation of the cam disk 47 swings the lower end of the guide rod and thus moves the picker from front to rear.

In furtherance of the desired simplicity of construction, the picker is arranged directly to contact the peripheral surface of a roll which dips into a body of gum in a gum box. The picker is moved along a path tangential to the roll while in contact with the gum coated periphery of the roll, thereby turning the roll so as to keep its peripheral surface supplied with gum. Thus other roll-driving means is dispensed with and but one element, to wit a single roll, is required for removing gum from the box and applying it to the picker.

The gum box 57 (Figs. 1 and 3) is supported within the frame above the magazine M. A gum-applying roll 58 is journaled in bearings carried by the box and is so arranged as to pick up gum from the box and apply it to the surfaces 32 of the picker as the latter is moved down in tangential relation to the roll, as hereinafter more fully described. Any appropriate means, not herein specifically illustrated, is provided for supporting the gum box in such a way that it may readily be removed for cleaning, as well as for adjusting it to maintain contact of the roll 58 with the body of adhesive within the box. Preferably the peripheral surface of the roll is of resiliently yielding material, for example, a rubber compound.

The labels are removed from the picker and delivered to the article to be labeled by means of a pneumatic transfer device or applier 60 (Fig. 3). This applier 60 may be of a customary type, comprising suction pad 61 having therein suction orifices which communicate with a chamber within a support 62 for the pad. This support is carried by one arm 63 of a bell crank lever fulcrumed to turn about a transverse shaft 64 and having a second arm 65 which is pivotally connected at 66 to the upper arm of a yoke 67. The upper end of a link 68 is arranged to slide in a guide bore in the lower arm of the yoke 67 and is urged upwardly relatively to the yoke by a coil spring 69. The lower end of the link 68 is arranged to slide in a guide bore in the upper arm 70 of a yoke 71, being urged upwardly relatively to the latter yoke by a coil spring 72, the link having a limiting collar 73 at its lower end. The lower end of the yoke 71 is pivotally connected to the forward end of a lever 74 which is fulcrumed at its rear end on a shaft 75 carried by the frame, the lever 74 having a cam follower roll 76 intermediate its ends which is received within a cam groove 77 (Fig. 5) in a cam disk 78 fixed to the shaft 10.

The arm 63 which supports the transfer device, carrier, or applier 60 is provided with a bore communicating with a chamber in the part 62, and a flexible conduit 79 leads from this bore to a valve housing V at the intake of pump 15.

After it has deposited a label upon the article,

the transfer device or applier returns to receive another label from the picker, and during this interval the label left resting upon the article is firmly pressed against the article by a presser device 80. This presser device may be of conventional type, if desired, comprising a pad 81, usually of yieldable material and contoured to correspond to the contour of the article to which the label is applied. This pad 81 is carried by a rigid bar 82 which is supported to move up and down toward and away from the article rest 8 by means of a pair of rock arms 83 and 84 which are pivotally connected to the bar 82 by spaced pivot pins 85 and 86 respectively. The rear end of the arm 83 is fulcrumed on a pin 87 carried by the machine frame. The arm 84 is longer than the arm 83 and fulcrumed upon a pin 88, and has a rearwardly directed extension 89 to which the upper end of a link 90 is adjustably united by a pin and slot connection at 91.

The lower end of link 90 is arranged to slide in a bore in the upper arm 92 of a yoke 93. It is urged upwardly, relatively to the yoke, by a coil spring 94 and has a limiting head or collar 95 at its lower end. The lower end of yoke 93 is pivotally connected at 96 to the lower end of a lever 97 fulcrumed at its forward end on a pin 98 carried by the frame, and has a cam follower roll 100 intermediate its ends which is received in a cam groove 101 (Fig. 9) in a cam disk 102 fixed to the drive shaft.

A bracket 103 (Fig. 1) supports a horizontal transverse shaft 104 upon which is mounted a lever device having the arms 105, 106 and 107 disposed substantially at right angles to each other. The arm 105 is provided with a roll 103 which engages the edge of a cam 109 fixed relatively to the lever 28 so as to be turned by actuation of said lever, the cam having a concentric dwell or locking portion 110. The arm 106 carries a roll 111 which is designed to engage a part carried by the arm 63 which supports the transfer device or applier 60. The rear end of the arm 107 is pivotally connected to the upper end of a link 112 (Fig. 1) whose lower end is arranged to slide in a bore in the upper arm 113 of a yoke 114, the link being urged downwardly relatively to the yoke by a coil spring 115. The lower end of the yoke is pivotally connected at 116 to a lever 117 fulcrumed on a pin 118 carried by the frame and having a cam follower roll 119 which is received in a cam groove 120 (Fig. 6) in a cam disk 121 fixed to the shaft 10.

The sequence of operations of the machine in applying a label to an article is substantially as follows, it being assumed that an article, for example a bottle B, has been placed in the article-receiving cradle or support 8 in readiness to receive a label, and that the picker 30 is at the upper limit of its stroke.

Assuming that the machine is just starting into operation, having previously been idle, it is desirable to have the machine perform several idle cycles of movement at the start in order that the picker may be supplied with an adequate amount of adhesive before it attempts to remove a label from the magazine. To permit such idle movement of the machine, the operator first raises the handle 29 thereby rocking the lever arm 26 (Fig. 1) and moving the link 24 upwardly, thus swinging the lever arm 24 upwardly and by means of the link 20 retracting the magazine M from its normal position. When in this rearward position the picker may go through its normal cycle of operations without contacting a label and thus

the picker may be supplied with an adequate coating of adhesive before it makes any attempt to remove a label from the magazine.

In thus swinging the arm 28 upwardly, the cam 109 is rotated so as to press the roll 108 downwardly thus swinging the arm 106 to the rear so that the roll 111 is no longer in position to hold the transfer device or applier 60 in the label transfer position. Since the spring 69 tends to swing the transfer device rearwardly, the removal of the roll 111 from its normal position permits the applier to move slightly back away from the picker path, so that the face of the applier will not be smeared with adhesive. The dwell portion 110 of the cam 109 serves to retain the parts in this abnormal position until the handle 28 is purposely moved downwardly again.

It will now be assumed that these preliminary operations, during which the picker has received a coating of adhesive, have been completed and that the handle 28 has been restored to the position shown in Fig. 1. The picker carriage 34 is now moved downwardly by the link 51, the guide 36 being held in such a position by the link 39 that the adhesive-receiving surfaces 32 of the picker plate move downwardly in a path which is substantially tangent to the surface of the gum roll 58. In thus moving past the gum roll the surfaces 32 are supplied with a coating of adhesive. As the picker plate passes below the gum roll 58 and reaches the lowest point in its path of travel, it is caused to dwell for a short time while the link 39 is so actuated by the cam 47 as to swing the lower end of the guide bar 36 to its most rearward position. This movement takes place while the picker is in registry with the forward end of the label magazine and causes the adhesively coated surface 32 of the picker to contact the forward label in the magazine. When the label has been contacted by the gum surface 32 so as to adhere to the latter, the lower end of the guide bar 36 is swung forwardly by the action of the cam 47 and immediately thereafter the cam 56 causes the label carriage to move upwardly until it registers with the applier pad 61 which is now in its rearmost position, as shown in Fig. 1. This upward movement of the picker carriage takes place in a path such that as the picker moves upwardly past the gum roll 58, the label, which is adherent to the picker, does not contact the gum roll. When the picker carriage has reached the upper end of its stroke with the picker in registry with the applier pad 61, the picker carriage dwells at this point, and the applier pad 61 is moved forwardly by the roll 111 so that the label adherent to the picker is caused to contact with the forward surface of the applier pad 61. At this instant control valves in a valve housing V (Fig. 4) of a type conventional in this art, are so manipulated, as to establish suction at the suction orifices of the applier pad 61 so that the label adheres to the pad more strongly than to the surfaces 32 of the picker. The applier 60 is now held in this position by the operation of the cams 78 and 121, while the picker commences its next down stroke. The picker moves downwardly while still in contact with the label. This movement of the picker in a path parallel to the face of the applier pad 61 and while the label is firmly attached to the applier pad, results in a uniform distribution of the adhesive over the surface of the label. If a picker such as that illustrated in Fig. 2a be employed, the adhesive is first applied to the label in a series of parallel stripes by means of the several spaced surfaces

32a of the picker. By this means it is possible to apply just sufficient adhesive to the label, while insuring its uniform distribution, and without danger of applying too much adhesive so that the adhesive will smear adjacent parts.

As soon as the picker carriage has descended far enough to clear the suction pad 61 of the applier, the transfer device or applier, including the suction pad 61 with the label adherent thereto, is swung downwardly by the operation of the cam 78 until the adhesively coated surface of the label is brought into contact with the upper surface of the bottle B, the parts of this instant in the operation being arranged as in Fig. 3, it being noted that at this time the picker carriage is in position for picking off a new label from the magazine. It will thus be evident that the picker follows a substantially triangular path, the gumming station being located at that side of the path which extends from the transfer point to the magazine.

Immediately after the label has been adhesively applied to the bottle, the suction at applier pad 61 is automatically broken and the applier 60 is swung backwardly to its normal position. As soon as the applier has cleared the path of the presser pad 81, the latter is moved downwardly by the action of the cam 102 so as firmly to press the label against the bottle to insure smooth and uniform adhesion. The presser pad 81 is then again raised to the position shown in Fig. 3, so as to permit the applier 60 to swing downwardly on the next cycle of operation.

While the picker guide 36 is herein specifically shown as pivoted to swing, it is obvious that an equivalent functional result could be obtained by mounting the guide 36 so as to move bodily, for example, in a direction perpendicular to its length in which case the path of the picker would be generally rectangular instead of triangular. However, the pivotal arrangement is simpler and is to be preferred. Likewise, as is customary in the art, the picker guide 36 may be fixed and the gum box and magazine so movable relatively to the fixed guide as to apply gum to the picker and to bring the endmost label in the magazine into operative contact with the picker, rather than to have the picker guide move, all with substantially the same functional effect as that described, although the pivoted picker guide is preferred by reason of its simplicity and to avoid practical difficulties incident to the moving of the gum box and magazine, especially in high speed machines.

While one desirable embodiment of the invention has been illustrated by way of example, it is to be understood that the invention is broadly inclusive of any and all modifications falling within the scope of the appended claims.

I claim:

1. A labeling machine having in combination a magazine, an adhesive type picker for removing labels from the magazine, means guiding the picker to move in a substantially rectilinear path, a pneumatic carrier operative to remove the label from the picker by suction, and means operative to swing the carrier in an arcuate path to deliver the label to a label-applying station.

2. A labeling machine having in combination a magazine, an adhesive type picker for removing labels from the magazine, an elongate rigid guide for the picker, means for moving the picker along the guide, a pneumatic carrier operative by suction to remove the label from the picker, a swinging arm supporting the carrier, and means for

swinging the arm to dispose the label with its gummed surface in contact with an article to be labeled.

3. A labeling machine comprising means for applying adhesive to one surface of a label, means for holding the label stationary by its unguammed surface, and means for spreading the gum substantially uniformly over the first surface of the label.

4. A labeling machine having a label magazine, a single adhesive type picker element of substantially the same size and shape as the label to be applied, means for applying gum to the picker element, an applier having a label-contacting surface of substantially the same size and shape as the label to be applied, means for registering the contact surface of the applier with the uncoated surface of a label adherent to the picker element, and means operative to cause the label preferentially to adhere to the applier while separating the picker from the applicator.

5. A labeling machine of the kind wherein an adhesively coated picker removes a label from a magazine and carries it to a transfer station where it is transferred to an applier and wherein adhesive is supplied to the picker on its way from the transfer station to the magazine, and having a support for the article to be labeled, characterized in that the picker and the applier each has a label-contacting surface which is of substantially the same shape and size as the label to be applied, and in having means operative to dispose said surfaces, respectively, at opposite sides of and in contact with a label at the transfer station.

6. A labeling machine of the kind wherein an adhesively coated picker removes a label from a magazine and carries it to a transfer station where it is transferred to an applier and wherein adhesive is supplied to the picker on its way from the transfer station to the magazine, and having a support for the article to be labeled, characterized in that the picker has a single adhesive-receiving surface of substantially the same size and shape as the label to be applied, the applier having a label-contacting surface of approximately the same size, and means for registering the label-contacting surfaces of the picker and applier with the label interposed between them.

7. A labeling machine comprising an adhesive type picker element and a magazine from which the picker withdraws labels one by one, a pneumatic carrier, means operative to dispose the picker and carrier at opposite sides of and in registry with a label at a transfer station, means operative to cause the label to adhere more strongly to the carrier than to the picker, and means operative to move the picker away from the transfer station along a path substantially parallel to the plane of the label while leaving the label attached to the carrier.

8. A labeling machine comprising a rigid part having a substantially flat adhesive-receiving face, means for applying adhesive to said face, means for contacting the adhesively coated face of said part with one side of a label, a carrier having a substantially flat label-engaging surface, means operative to bring said latter surface into contact with the unguammed surface of the label, means operative to adhere the label to the carrier, and means operative to move said first-named part relatively to the label and in a plane substantially parallel to the plane of the label so as to spread the gum uniformly over the label, and means for moving the carrier with the coated

surface of the label exposed so as to convey the label to an applying station.

9. In a machine of the class described, an adhesive type picker having a gum-receiving surface, means for applying adhesive to said surface, means for bringing the adhesively coated surface of the picker into contact with a label, means operative to hold the label stationary by its unguammed surface, and means operative to spread the gum substantially uniformly over the picker-contacting surface of the label while the label is so held.

10. In a machine of the class described, an adhesive type picker having a gum-receiving surface, means for applying gum to said surface, means operative to bring the coated surface of the picker into contact with a label, means operative to hold the label stationary, and means operative to slide the picker relatively to the label while the label is so held, thereby to spread the adhesive.

11. In a labeling machine of the kind wherein an adhesively coated picker removes a label from a magazine and carries it to a transfer station where it is transferred to a pneumatic applier, and wherein adhesive is supplied to the picker on its way from the transfer station to the magazine, and having a support at the front of the machine for the article to be labeled, an approximately vertical elongate guide rearward of the support for guiding the picker in its cycle of movements, the transfer station being above the level of the article support, the magazine being below the level of the support and the adhesive-supplying means being so located that as the picker moves from the transfer station to the magazine, it receives a supply of adhesive, and means for actuating the picker.

12. A labeling machine of the kind in which an adhesively coated picker removes a label from a magazine and delivers it to an applier at a transfer station, and having means for supplying adhesive to the picker and means for moving the picker through a definite cycle, characterized in that said picker-moving means comprises an elongate picker guide pivoted to swing about a fixed axis, two driving cams, and parts actuated by the cams to move the picker along said guide in a substantially polygonal path having the magazine at one angle and the transfer station at another angle, and with the adhesive-supplying means adjacent to that part of said path which connects said angles.

13. In a labeling machine of the kind in which an adhesively coated picker removes a label from a magazine and delivers it to an applier at a transfer station, an elongate guide along which the picker slides, means pivotally supporting the guide at one end, means for moving the picker along the guide, and means for swinging the picker about its pivotal support.

14. In a labeling machine of the kind in which an adhesively coated picker removes a label from a magazine and delivers it to an applier at a transfer station, an elongate movable guide along which the picker slides, means for moving one end at least of the guide to and from the magazine, and means operative to move the picker along the guide from the transfer station into operative registry with the magazine.

15. A labeling machine of the kind wherein an adhesively coated picker removes a label from a magazine, carries it to a transfer station where it is transferred to a pneumatic applier, and wherein adhesive is supplied to the picker on its way from the transfer station to the magazine, characterized in having an elongate guide for the

picker, means pivotally supporting the guide at a point adjacent to the transfer station, cam actuated means for moving the picker along the guide, and cam actuated means operative to swing the guide, said cam actuated means being so relatively arranged that the picker traverses a substantially triangular path having the transfer station and magazine at opposite ends of that side of the path at which the adhesive-supplying means is located.

16. A labeling machine of the kind wherein an adhesively coated picker removes a label from a magazine, carries it to a transfer station where it is transferred to a pneumatic applier, and wherein adhesive is supplied to the picker on its way from the transfer station to the magazine, characterized in having an elongate movable guide for the picker, cam actuated means for moving the picker along the guide, and cam actuated means for so moving the guide, said cam actuated means being so constructed and arranged as to cause the moving picker to pass in adhesive-receiving relation to the adhesive-supplying means and thereafter to engage the coated surface of the picker with the endmost label in the magazine.

17. A labeling machine of the kind wherein an adhesively coated picker removes a label from a magazine, carries it to a transfer station where it is transferred to a pneumatic applier, and wherein adhesive is supplied to the picker on its way from the transfer station to the magazine, and a spring which tends to move the applier away from the transfer station, characterized in having a movable stop normally preventing movement of the applier by the spring and means operative at will to make said stop inoperative, thereby to prevent operative approach of the picker and applier at the transfer station while the machine is in operation.

18. A labeling machine of the kind in which an adhesively coated picker removes a label from a magazine and delivers it to an applier at a transfer station, a guide for the picker, said guide being pivoted to swing about an axis adjacent to the transfer station, the guide being of a length to provide a path for the picker extending from the transfer station to the magazine, a gum roll for applying adhesive to the picker, cam actuated means for moving the picker along said guide, and cam actuated means for swinging the guide, the means for moving the guide and picker being so constructed and arranged that as the picker moves from the transfer station to the magazine it passes the adhesive-supplying means in operative relation to the latter and in returning to the transfer station passes the adhesive-supplying means out of operative relation to the latter.

19. A labeling machine of the kind in which labels held in a magazine are removed therefrom one after another by an adhesively coated picker, transferred from the latter to a pneumatic applier, and applied by the latter to the article to be labeled, and wherein a roller supplies adhesive to the label-engaging surface of the picker and an elongate movable rigid guide for the picker, characterized in having cam actuated means for moving the guide and in having cam actuated means for moving the picker along the guide, said cam actuated means being so constructed and related that the picker is moved in one direction along the guide in tangential relation to the roller so as to receive adhesive from the latter and then is contacted with the endmost label in the magazine and is then retracted from the magazine

and moved back along the guide out of contact with the roller, and cam actuated means for moving the applier into contact with the ungummed surface of the label adherent to the picker.

5 20. A labeling machine of the kind wherein an adhesively coated picker removes a label from a magazine, carries it to a transfer station where it is transferred to a pneumatic applier, and wherein adhesive is supplied to the picker on its way from the transfer station to the magazine,

10 characterized in having cam operated applier actuating means normally operative to dispose the applier in label-transferring relation to the picker at the transfer station, means tending to prevent operative approach of the applier and picker while the picker continues to perform its normal cycle of operations, and a manually controlled stop element normally positioned to insure operative approach of the applier and picker.

15 21. A labeling machine of the kind wherein an adhesively coated picker removes a label from a magazine, carries it to a transfer station where it is transferred to a pneumatic applier, and wherein adhesive is supplied to the picker on its way from the transfer station to the magazine,

20 and in which continuously acting means causes the picker to perform its cycle of movements, characterized in that the magazine is movable toward and from operative position, and in having link and lever means normally operative to hold the magazine in its operative position but constructed and arranged to move the magazine to inoperative position so as to prevent contact of the picker with a label in the magazine during a plurality of successive cycles of operation of the machine.

25 22. A labeling machine of the kind wherein an adhesively coated picker removes a label from a magazine and carries it to a transfer station where it is transferred to a pneumatic applier, and wherein adhesive is supplied to the picker on its way from the transfer station to the magazine, and in which continuously acting means causes the picker to perform its cycle of movement, characterized in having manually actuatable ring and lever means operative at will and while the picker continues its cycle of movements, to move the magazine and applier out of operative relation to the picker path.

30 23. In a labeling machine of the kind wherein an adhesively coated picker removes a label from a magazine and carries it to a transfer station where it is transferred to a pneumatic applier, and wherein adhesive is supplied to the picker on its way from the transfer station to the magazine, an article support, and a movable label presser, a drive shaft having thereon cams for actuating the picker, applier and presser, and means including yieldable connections for transmitting motion from the cams to the picker, presser and applier, respectively.

35 24. A labeling machine comprising means for applying adhesive to spaced fractional portions of one surface of a label, means for holding the label stationary by its ungummed surface, means for spreading the gum substantially uniformly over the first surface of the label, and means for bringing the gummed surface of the label into contact with the article designed to receive it.

40 25. A labeling machine of the kind wherein an adhesively coated picker removes a label from a magazine, carries it to a transfer station where it is transferred to a pneumatic applier, and wherein adhesive is supplied to the picker on its way from the transfer station to the magazine,

characterized in that the picker is shaped so as initially to apply the adhesive to a fractional portion only of the surface of the label, means operative to cause the picker to dwell at the transfer station while the label is engaged by the applier, and means operative to move the picker in sliding relation to the label thereby to spread the adhesive over the entire surface of the label.

26. In a machine of the class described, an adhesion type picker whose adhesive surface is divided into a series of spaced parallel narrow faces, means for applying adhesive to said faces of the picker, and means operative to slide the picker relatively to a label contacting the picker thereby to spread the adhesive deposited on the label by said narrow faces, so as to cover substantially the entire label.

27. A labeling machine of the kind wherein an adhesively coated picker removes a label from a magazine, carries it to a transfer station where it is transferred to a pneumatic applier, and wherein adhesive is supplied to the picker on its way from the transfer station to the magazine, characterized in that the picker has a series of spaced, parallel, elongate, adhesive-receiving faces all in the same plane, and means operative to move the picker relatively to the label while keeping said faces in contact with the label and in a direction perpendicular to the lengths of said surfaces thereby to spread the adhesive uniformly over the label.

28. A labeling machine of the kind wherein an adhesively coated picker removes a label from a magazine, carries it to a transfer station where it is transferred to a pneumatic applier, and wherein adhesive is supplied to the picker on its way from the transfer station to the magazine, characterized in that the adhesive-receiving face of the picker is shaped to apply the adhesive to the label as a plurality of parallel spaced stripes, and means operative to move the picker relatively to the label thereby to spread the adhesive to form a substantially uniform coating upon the surface of the label.

29. A labeling machine of the kind wherein an adhesively coated picker removes a label from a magazine, carries it to a transfer station where it is transferred to a pneumatic applier, and wherein adhesive is supplied to the picker on its way from the transfer station to the magazine, characterized in having picker-actuating means operative to cause the picker with a label adhering thereto to dwell at the transfer station, means operative to engage the pneumatic applier with the uncoated face of the label at the transfer station, and means operative to slide the picker relatively to the label while the latter is held stationary by the applier thereby to spread the adhesive.

30. A labeling machine of the kind wherein an adhesively coated picker removes a label from a magazine, carries it to a transfer station where it is transferred to a pneumatic applier, and wherein adhesive is supplied to the picker on its way from the transfer station to the magazine, characterized in having means operative to hold the pneumatic applier stationary at the transfer station, and means operative to move the picker in a path parallel to the label-engaging surface of the applier while the label is held stationary by the latter, thereby to spread the adhesive evenly over the face of the label.

31. A labeling machine of the kind wherein an adhesively coated picker removes a label from a magazine, carries it to a transfer station where it is transferred to a pneumatic applier, and

wherein adhesive is supplied to the picker on its way from the transfer station to the magazine, characterized in having means operative to move the picker relatively to the label in a path parallel to the label and while in contact with the label, thereby to spread the adhesive uniformly over the label.

32. A labeling machine of the kind wherein an adhesively coated picker removes a label from a magazine, carries it to a transfer station where it is transferred to a pneumatic applier, and wherein adhesive is supplied to the picker on its way from the transfer station to the magazine, and wherein the applier swings in an arcuate path, characterized in having means operative to hold the applier stationary at the transfer station with its label-receiving surface parallel to the adhesively coated surface of the picker, and means operative to move the picker in a path parallel to the plane of the label while in contact with the label and while the label is held stationary by the applier, thereby to spread the adhesive uniformly over the label.

33. A labeling machine including a roll whose peripheral surface is coated with adhesive, a picker having an adhesive-receiving surface, means for moving the picker in a plane tangent to the roll so that the surface of the picker substantially contacts the roll and receives adhesive from the latter, means for moving the coated surface of the picker into contact with a label so that the latter adheres to said surface, a pneumatic applier, means for moving the applier into registry and contact with the uncoated surface of the label, means for creating suction at the applier to cause the label firmly to adhere to the latter, means for sliding the picker relatively to the applier substantially in the plane of the label and while in contact with the latter, thereby to spread the adhesive, means for moving the applicator with the pneumatically adherent label so as to contact the gummed surface of the label with the article intended to receive the label, means for breaking the suction at the applier, means for retracting the applier, and means for applying pressure to the label to insure its adhesion to the article.

34. A labeling machine comprising a roll whose peripheral surface is designed to receive fluid gum, means supplying gum to the roll, a picker having a plurality of spaced gum-receiving faces, means for moving the picker in a plane substantially tangent to the roll thereby to apply gum to the picker faces, means for moving the picker so that its gummed faces contact and adhesively hold a label, a pneumatic applier, means for moving the picker and applier relatively thereby to cause the ungummed surface of the label to contact the applier, means creating a suction at the applier thereby to adhere the label to the applier, means for moving the picker relatively to the applier, substantially in the plane of the label, thereby to spread the gum, means for moving the applier with the label adherent thereto so as to dispose the gummed surface of the label in contact with the article designed to receive it, means for releasing the suction and for retracting the applier, and means for pressing the label against the article.

35. A labeling machine comprising a label magazine designed to hold a plurality of labels, a gum-applying roll, means for supplying gum to the roll, a picker, means for moving the picker along a path such that it receives gum from the roll, means for moving the picker with its gummed surface into registry with the label mag-

azine, means for advancing the picker to cause its gummed surface to engage the endmost label in the magazine, means for retracting the picker from the magazine with a label adherent thereto and for moving it to a transfer station, a pneumatic applier, means for so relatively moving the applicator and picker at the transfer station as to cause the ungummed surface of the label to contact the applier, means for creating suction at the applier to cause the label to adhere to the applier, means for moving the picker in sliding relation to the label held by the applier, thereby to spread the gum over the label, means for moving the applier with the adherent label so as to contact the gummed surface of the label with the article designed to receive the label, means for breaking the suction at the applier and for retracting the applier, and means for applying pressure to the label.

36. A labeling machine comprising a rigid part having a substantially flat adhesive-receiving face, means for applying adhesive to said face, means for contacting the adhesively coated face of said part with one side of a label, a second part having a substantially flat label-engaging surface, means for bringing said surface of said latter part into contact with the ungummed surface of the label, relatively moving the label and the first-named part so as to spread the gum uniformly over the label, and means for conveying the label, with its gummed surface exposed, to an applying station.

37. A labeling machine comprising a picker having a gum-receiving face, means providing a supply of fluid gum, means operative to move the

picker and gum supply so as to apply gum to the gum-receiving face of the picker, means for relatively moving the picker and label to cause the label to adhere to the gummed face of the picker, a pneumatic applier, means for moving the applier and picker into registry, and so as to contact the ungummed surface of the label with the applier, means for creating suction at the applier to cause the label to adhere to the latter, means for moving the picker and applier relatively and parallel to the plane of the label thereby to cause the picker to spread the gum over the label, means for moving the applier with the label pneumatically attached to it to a position such as to contact the gummed surface of the label with the article designed to receive it, means for releasing the suction at the applier, means for retracting the applier thereby to leave the label on the article, and means for pressing the label against the article.
